H. A. DOUGLAS,
CIRCUIT CONNECTOR,
APPLICATION FILED AUG. 15, 1918.

1,422,257.

Patented July 11, 1922.

Inventor:
Harry A. Douglas.
By L. L. Cragg, Atty.

UNITED STATES PATENT OFFICE.

HARRY A. DOUGLAS, OF BRONSON, MICHIGAN.

CIRCUIT CONNECTOR

1,422,257.

Specification of Letters Patent.

Patented July 11, 1922.

Application filed August 15, 1918. Serial No. 250,022.

To all whom it may concern:

Be it known that I, HARRY A. DOUGLAS, citizen of the United States, residing at Bronson, in the county of Branch and State 5 of Michigan, have invented a certain new and useful Improvement in Circuit Connectors, of which the following is a full, clear, concise, and exact description.

My invention relates to devices for establishing or extending circuits and is of particular service in joining two circuit sections such as an incandescent lamp and current conducting cord, though the invention is not to be limited to such use.

15 My invention has for its object the simplification and improvement of means whereby circuit conducting cords may be brought into circuit continuing or establishing connection. In carrying out my invention I employ an assembling shell, a contact carrier connected with the shell, a tubular conductor within the contact carrier and extending longitudinally of the shell, a circuit extending plug receivable in one end of 20 the tubular conductor, said contact carrier having a transverse bore intersecting its bore that receives the tubular conductor which itself has a lateral opening communicating with said transverse bore, a plunger 25 contact which projects through the lateral opening in the tubular conductor into the bore thereof to be engageable with said circuit extending plug, and a spring in said transverse bore which presses said plunger 30 contact against the plug.

When the device is employed to couple the circuit extending plug with another contact carrier having a rigid contact, such for example as is included in the formation of an 40 incandescent lamp, the additional contact carrier and shell are provided with interengaging formations, preferably bayonet pins and slots, for separably coupling them and another plunger contact is disposed in the 45 tubular conductor and is spring pressed into engagement with a contact upon the additional contact carrier.

I will explain my invention more fully by reference to the accompanying drawing 50 showing the preferred embodiment thereof and in which Fig. 1 is a view in longitudinal section of a circuit connector made in accordance with the preferred embodiment of the invention, an incandescent lamp being 55 shown in elevation within the forward end of the shell; and Fig. 2 is a sectional view on

line 2—2 of Fig. 1. The drawing shows a single pole device to which, however, the invention is not to be limited.

Like parts are indicated by similar characters of reference in both views.

The circuit conductor illustrated includes a cylindrical assembling shell 1, preferably metallic and necessarily so in a single pole construction. A cylindrical contact carrier 65 2, preferably of insulating material, is connected with the rear end of the shell. In the form of the invention shown this contact carrier and the shell are permanently assembled by punching portions 3 of the shell into 70 the contact carrier. A metallic tube 4, constituting a conductor, extends longitudinally of the shell and through the contact carrier, and as the device illustrated is a single pole device, the bore of the contact carrier that 75 receives the tubular conductor is co-axial with the shell and contact carrier. The tubular conductor is desirably formed by longitudinally drilling solid rod, a bridge portion 5 being left at an intermediate portion of the conductor 4 for engaging the inner end of the coiled spring 6 which is disposed in the front portion of the tubular conductor. The front end of the tubular conductor has a shoulder 7 surrounding the 80 entrance to the bore of this tubular conductor at its front end. The plunger contact 8 projects through the front end of the conductor 4 and has an enlargement 9 within the tubular conductor for limiting the extent 85 to which this contact may be outwardly or forwardly thrust by the spring 6 whose forward end is in pressing engagement with said contact. A second contact carrier 10 is illustrated, this contact carrier having bayonet 90 pins 11 receivable within bayonet slots 12 provided in the forward end of the shell 1. The contact carrier 10 has a contact 13 engaged by the outwardly and forwardly 95 spring pressed contact 8 and constituting one 100 terminal of the incandescent lamp bulb filament 14 whose other terminal is connected with the metallic sheath 15 surrounding the contact carrier 10 and in electrical contact with the metallic shell 1 which is connected 105 with one terminal of the source of current which is to supply the lamp. A circuit extending plug 16 is connected, by means of the cord conductor 17, with the other terminal of said source of current and is receiv- 110 able in the rear portion of the tubular conductor 4. This plug has an annular groove

18 at its forward or inner end. A transverse bore 19 extends in the plane of and intersects the longitudinal bore in the contact carrier 2 that contains the conductor 4, this 5 conductor having a lateral opening 20 aligned with but narrower than the transverse bore 19. A second plunger contact 21 projects through this lateral opening in the tubular conductor 4 into the bore of this 10 conductor to be engageable in the annular groove 18 in the circuit extending plug. This second plunger contact has a cup shaped flange portion 22 which is upon the exterior of the tubular conductor 4 to limit 15 the extent to which this plunger contact may project into the bore of this conductor when the plug 16 is withdrawn. A coiled spring 23 is disposed in the inner end of the transverse bore 19 and engages the cup shaped 20 flange of the contact 21 thereby to press this contact toward the tubular conductor 4 and against the groove portion 18 of the plug.

In the preferred embodiment of the invention the contact carrier 2 extends rearwardly 25 beyond the shell 1. Whenever the translating device 14 is to be included in circuit the simple plug 16 is readily inserted within the conductor 4 into engagement with the contact 21 which not only serves electrically to 30 connect the conductor 4 and the plug 16 but also serves mechanically to maintain the assembly of these parts. When the translating device 14 is to be disconnected the plug is merely withdrawn against the compara-

tively slight resistance offered by the spring 35 23 to the removal of the plug.

While I have herein shown and particularly described the preferred embodiment of my invention I do not wish to be limited to the precise details of construction shown as 40 changes may readily be made without departing from the spirit of my invention, but having thus described my invention I claim as new and desire to secure by Letters Patent 45 the following:—

A circuit connector including a contact carrier having a recess therein, a longitudinally recessed conductor extending through the carrier and intersecting the recess of the carrier at right angles thereto, said conductor having a passage therein of less diameter than the recess of the carrier and connecting the conductor recess with the carrier recess, a latch slidable in the carrier recess and having a reduced forward end operating in the 55 passage of the conductor and forming a shoulder engageable with the conductor to limit locking movement of the latch, and a spring between the latch and the base of the carrier recess operating to project the latch 60 against a circuit extending plug inserted in the recess of the conductor to force said plug into firm contact with the conductor.

In witness whereof, I hereunto subscribe my name this 12th day of August A. D., 65 1918.

HARRY A. DOUGLAS.
